AUTOMATIC ROLL ADJUSTMENT

John Blair Sutton, Bellefonte, Pa., assignor to
 Sutton Engineering Company, Pittsburgh, Pa.,
 a corporation of Pennsylvania

Application September 3, 1948, Serial No. 47,702

10 Claims. (Cl. 153—60)

1

This invention relates to automatic angular adjusting of the axes of rotation of the rolls in straightening machines of the cross-roll type where concave contoured rolls are positioned at an angle in relation to round stock passed through the machine.

The object of the invention is to provide automatic means for the proper angular adjustment of the rolls in machines of the above indicated sort simultaneously with roll adjustment to regulate the pass diameter for various diameters of round stock.

This automatic angling may be accomplished by various specific means and is applicable to any machine of the indicated sort in the use of which it is necessary to change the angular position of the axes of rotation of the rolls in adjusting the pass to various stock diameters.

In the accompanying drawings:

Fig. I is a schematic view showing the pivoting of arms carrying the secondary rolls of a three-roll-pass straightening machine and including means for automatically effecting angular axial adjustment of the rolls of a pass in correspondence with adjustment of the rolls toward and away from the center of the pass line in accommodation to different stock diameters.

Fig. II is a schematic view showing a conventional arrangement of a cross-roll straightening machine comprising two of the three-roll groups shown in Fig. I and an intermediate pressure roll.

Fig. III is a schematic view showing the primary and secondary roll of one pass of a five-roll straightening machine and illustrating other means for automatically effecting angular adjustment of the rolls; it being understood that the arrangement shown in this figure of the drawings is applicable to cross-roll straightening machines of simple two-roll, three-roll or four-roll types.

Fig. IV is a schematic view showing the conventional arrangement of the rolls of a five-roll straightening machine.

Fig. V is a schematic view of a roll, showing the line of contact between the concave portion of said roll and round stock of a given diameter.

Fig. VI is a schematic view of a roll, shown for the purpose of illustrating the change of inclination of said roll for different diameters of stock.

Fig. VII is a schematic view which shows the angular adjustment of a roll of a straightening machine in accommodating to differences in stock diameters.

Fig. VIII is an end elevation of a straighten-

2

ing machine showing one specific embodiment of my invention in a seven-roll, three-roll-pass cross-roll straightening machine.

Fig. IX is a front elevation of the said machine looking from the right of the sheet on which Fig. VIII is shown.

Fig. X is a fragmentary sectional view taken through a primary roll showing a preferred method of mounting said roll to the frame of the machine shown in Fig. VIII.

Fig. XI is a fragmentary sectional view taken through one of the secondary rolls of the machine shown in Fig. VIII and showing a preferred method of mounting the same.

A number of means for effecting automatic angular axial adjustment may be used with various straightening machine structures, preferred embodiments of the invention for various roll arrangements being herein shown. All such means, however, stem from a common principle of interconnecting an element which causes or moves in adjustment of the rolls to vary the pass diameter with structure for automatically adjusting the angular position of the rolls. In the drawings I have illustrated certain embodiments such as rods connected to the frame of the machine and to means for adjusting the pass diameter and to the roll brackets, as shown in Figs. I, VIII and IX; and as interconnected gears, as shown in Fig. III. Automatic adjustment of the angular position of the rolls may also be achieved by the use of cams, links, screws, helical keyways and the like.

Briefly to describe my invention I have a direct connection between the frame of the machine and roll brackets which after initial adjustments automatically adjusts the angular position of the rolls simultaneously with the adjustment of the rolls to various bar diameters.

This operation of axial angular adjustment is accomplished without the need of loosening or tightening lock nuts or the like, and without any adjustments other than the secondary roll adjustments toward and away from the center of the pass to suit the diameter of the stock.

It is to be noted that for better illustration of the principle involved, Figs. I to VII inclusive show schematically various means responding to the principle of automatic angling with pass diameter adjustment for various stock diameters.

Referring first to Fig. I of the drawings, I have there shown a preferred embodiment of my invention. This figure shows a straightening machine in which passes composed of three rolls are included. In this arrangement a three-roll pass

55

is made up of a primary roll 1 and secondary rolls 2 and 3, supported by their roll brackets 4, 5 and 6 respectively. The secondary rolls are adjusted toward and away from the center of the pass by means of handwheel 7 which is keyed to screw 8 which has left hand and right hand threads on opposite ends. As handwheel 7 is operated, arms 9 and 10 swing with pivot shafts 11 and 12 altering the size of the pass to suit the diameter of the stock 13. Simultaneously with the adjustment of the rolls for a specified stock diameter, the angular axial adjustment of the rolls is effected. Roll bracket 4 carrying primary roll 1 is equipped with a lug 14 having a pivot pin 15 to which is attached rod 16. Turnbuckle 17 interconnects rod 16 with rod 18 which is attached to pin 19 on the lever 20 of arm 9. As arm 9 pivots with shaft 11 for accommodation of various stock sizes the motion is transmitted through lever 20 and rods 19 and 16 to lug 14 thus pivoting bracket 4 on its center 21 and changing the angle of primary roll 1.

The secondary roll 2 mounted on bracket 5 is angularly adjusted by means of rods 22 and 24 which are interconnected by turnbuckle 23. Rod 22 is attached to bracket 5 through pivot pin 25 which is fastened to said bracket. Rod 24 is attached to pivot pin 26 on stationary frame 27. When adjustment is made through handwheel 7 for various stock diameters, motion is transmitted through rods 24 and 22 to bracket 5 thus pivoting said bracket on its center 28 and changing the angle of secondary roll 2.

Secondary roll 3 is angularly adjusted in a manner identical to that used for secondary roll 2, except that the mechanism for angular axial adjustment is situated on the far side of arm 10, so that the angular adjustment of the two secondary rolls is opposite in sense.

The initial setting of the roll angle of all three rolls is maintained by the turnbuckles 17, 23 and 29. The ratio of angular change to in-and-out movement of the rolls may be altered by adjusting the pivot pins 19, 26 and 30 in slots 31, 32 and 33 in which respectively they lie. Regulation necessitated by the wearing of the rolls may be made in like manner.

Fig. II shows in schematic side elevation the conventional roll arrangement of a straightening machine comprising a three-roll pass as shown in Fig. I. Primary roll 1 and secondary rolls 2 and 3 form the pass at one end of the machine. The rolls 1a, 2a and 3a are at the opposite end of the machine and are adjusted in the same manner as rolls 1, 2 and 3. Intermediate pressure roll 34 is to be understood as adjusted toward and away from the pass line to accommodate various stock diameters. In order to effect the automatic angular adjustment, the mechanism for effecting angular adjustment of said roll may be connected to the means for causing its in-and-out adjustment.

In Fig. III I have illustrated another method of effecting automatic angular adjustment of the rolls. This view shows in schematic end elevation a primary roll 35 and a secondary roll 36 which may form one pass of a straightening machine of the five cross-roll type. Roll 36 is laterally adjusted by handwheel 37 which is keyed to the end of screw 38. Screw 38 is positioned on the frame 39 by nut 40 and collar 41. Screw 38 engages threaded bore 42 in the stem end of bracket 43. Movement of handwheel 37 will adjust the secondary roll laterally to suit the diameter of stock which is designated by numeral

44 and simultaneously effect the automatic angular adjustment of the rolls. Roll inclination of the secondary roll 36 is caused in desired order by pin 45 on roll bracket 43 and cam slot 46 on plate 47 which is secured to frame 39 by screws 48.

Pinion 49 which is keyed to screw 38 engages gear 50 which is keyed to screw box 51 rotatable in the machine frame. By rotating screw box 51 through gear 50 adjusting screw 52 is moved longitudinally in the screw box. Link 53 at one end is fastened to screw 52 and its opposite end engages pin 54. Pin 54 is attached to arm 55 which is free to swing on fixed pivot 56. Arm 55 also engages pin 57 which is securely fastened to roll bracket 58 carrying primary roll 35. It can clearly be seen that when handwheel 37 is operated for various stock diameters, the inclination of the secondary roll 36 is effected by the movement of pin 45 along slot 46 and the inclination of the primary roll is effected by the swinging of arm 55 on its pivot 56.

For the initial setting of the roll angle in relation to the lateral movement of the secondary rolls or for adjusting the angle necessitated by the wearing of the rolls, the set angle of the primary roll 35 can be adjusted by removing pinion 49, permitting screw 38 to be turned without moving gear 50. The set angle of the secondary roll can be adjusted by adjusting guide plate 47 in slots 59 through which the fastening screws 48 engage the main frame of the machine. It may be noted that if it is desired automatically to adjust the angular position of an intermediate pressure roll in organizations as shown in Figs. II and IV this structure provides one convenient means for so doing.

It may also be desirable to adjust the ratio of change in the roll angle with respect to pass diameter adjustment. The ratio of angular adjustment of the primary roll 35 can be regulated by adjusting the position of pin 54 in slot 60 of arm 55. The ratio of angular adjustment of the secondary roll can be regulated by changing the pitch of slot 46 in guiding plate 47 by tilting guiding plate 47 slightly.

Fig. IV is a schematic plan view showing the conventional arrangement of the five-roll group shown in Fig. III. Primary roll 35a of secondary roll 36a are on the opposite end of the machine from rolls 35 and 36 and are adjusted both laterally and angularly in the same manner in which rolls 35 and 36 are adjusted. Intermediate pressure roll 61 may be adjusted automatically in some suitable manner, as by the means noted above.

In Fig. V I have illustrated the inclination of a roll 62 to a bar, or tube, 63 of a given diameter to give a line of contact of said bar with the concave portion of said roll between points a and b. If, however, the diameter of the bar should be changed, the inclination of the roll would also have to be changed to maintain a line of contact between points a and b.

Referring now to Fig. VI, if the bar is smaller in diameter than the bar, or tube, 63 of Fig. V, the angle designated by c must be decreased to maintain a line of contact between the bar and the concave portion of the roll between points 70 a and b. However, if the bar is larger in diameter than that originally mentioned, the angle designated by c must be increased to maintain a line of contact between the bar and the concave portion of the roll between the points a and b.

Fig. VII shows the angular adjustment of a

roll in accommodating to difference in diameter from stock of lesser diameter 64 to stock of greater diameter 65. Angle *d* shows the angular relation of the roll to the lesser diameter stock 64 and angle *e* shows the angular relation of the roll to greater diameter stock 65. Angle *f* is the angle through which adjustment is made in accommodating to stock between these diameters. It is to be understood that these two exemplary stock diameters do not of necessity include the diameter range of stock on which a machine of the illustrated sort can operate. Also in any machine the angle through which adjustment should be made will vary with the normal, or mean, roll inclination which is used and with the stock sizes on which the machine is designed to operate. Also it should be noted that the degree of roll angularity bears a relation to the contour of the roll, and that a nice adjustment of angularity requires accommodation to changes in contour as the roll is worn down in service.

In Figs. VIII and IX I have disclosed a straightening machine similar to that of my previous application Serial No. 705,778, filed October 25, 1946, which has matured into Patent No. 2,455,-391, granted December 7, 1948, to which I have applied my present invention.

Briefly to describe the adjustment of the cross rolls of that machine for various stock diameters, the turning of shaft 66 through screw boxes 67 and 68 moves the arms 69 and 70 to which the secondary rolls 71 and 72 are mounted. Arms 69 and 70 swing respectively about horizontal pivot shafts 73 and 74. Convergent inward swinging of arms 69 and 70 causes secondary rolls 71 and 72 to approach the primary roll 76 of the pass to decrease the pass diameter, and conversely outward divergent swinging of the arms increases the pass diameter. Simultaneously with the adjustment of the rolls for a specified stock diameter the angular adjustment of the rolls is effected.

Roll bracket 75 carrying primary roll 76 is secured to a backing plate 77 which is equipped with a lug 78 having a pivot pin 79 to which is attached rod 80. Turnbuckle 81 interconnects rod 80 with rod 82. Rod 82 is secured to a sliding bracket 83 through universal joint 84. Screws 85 fasten bracket 83 to lever 86 which is keyed to pivot shaft 74 with which arm 70 swings.

As arm 70 pivots with shaft 74 for adjusting the pass diameter in accommodation to various stock sizes, the motion is transmitted through lever 86 and rods 82 and 80 to lug 78, thus swinging backing plate 77 and roll bracket 75 to change the angle of the primary roll.

For initial setting of the angle of primary roll 75 in relation to the pass-diameter determining movement of the secondary rolls or for adjusting the angle necessitated for the wearing of the rolls, the angular setting of primary roll 76 can be altered by turnbuckle 81. The ratio of angular roll adjustment to pass diameter adjustment may be regulated by adjusting bracket 83 up or down on lever 86 to shorten or lengthen the arm acting on rod 82 to shorten or lengthen the stroke of the divided rod 80-82.

The secondary roll 71 being mounted on bracket 87 which is secured to backing plate 88 is angularly adjusted by means of rods 89 and 90 which are interconnected by turnbuckle 91. Rod 89 is attached to backing plate 88 through universal joint 92. Rod 90 is secured to stationary frame element 93 through universal joint 94. The end portion of universal joint 94 is in

the form of a bracket designated by numeral 94a which is slidably mounted in frame element 93 and is secured to the frame element by means of screws 95. When adjustment is made for various stock diameters, motion will be transmitted through divided rod 89-90 to backing plate 88 and roll bracket 87, thus turning said bracket on its center and changing the angle of secondary roll 71.

Secondary roll 72 is angularly adjusted in a manner identical to that used for secondary roll 71.

To accomplish opposite angular adjustment of the secondary rolls, the fixed points or bracket 15 94a is located toward and outside of the machine and outwardly beyond pivot point 73 of swinging arm 69, while corresponding bracket 97a is located further inward of the machine and inwardly of pivot point 74. It can be seen clearly that 20 as the arms 69 and 70 carrying secondary rolls 71 and 72 swing divergently outward, their movement acts to secure the desired angular adjustment. As arm 69 swings outwardly to accommodate larger stock diameters, its upper end 25 swings away from the vertical axis of the pass. In so doing it swings the upper end of divided rod 89-90 outwardly, and swings it about its center in frame element 93 and bracket 94a. This movement increases the effective length of the 30 rod, causing it to bear upwardly on roll bracket 87 so to rotate the bracket as to increase the angularity of roll 71 in its functional direction. As arm 70 swings outwardly away from the vertical axis of the pass it swings the upper end of 35 divided rod 116-117 outwardly about its center in bracket 97a which decreases the effective length of the rod, causing it to pull downwardly on roll bracket 107 and increase the angularity of roll 72 in its functional direction. The movement of the arms 69 and 70 inwardly to accommodate smaller stock diameters would reverse the above procedure and decrease the angularity of the secondary rolls in their functional direction.

For the initial setting of the roll angle in relation to the movement of the secondary rolls or for adjusting the angle necessitated by the wearing of the rolls, the angle of the secondary rolls 71 and 72 can be altered by adjusting turnbuckles 91 and 96. The ratio of angular change to in-and-out movement of the rolls may be altered by loosening screws 95 and adjusting bracket 94a and corresponding bracket 97a along dovetail ways, or the like 98 and 99 in frame elements 93 and 93a.

55 Intermediate pressure roll 100, Fig. IX, may be adjusted toward and away from the pass line to accommodate various stock diameters. In order to effect the angling of this roll automatically, the mechanism for effecting axial angular adjustment said roll may be connected to the means for causing its in-and-out adjustment, as has been indicated above with respect to roll 35 shown in Fig. III.

In Fig. X I have illustrated the mounting of the 65 primary roll. Primary roll 76 is mounted in bracket 75 which is secured to a backing plate 77 by means of screws 101. The backing plate is held against frame 102 by stud 103, nuts 104 and 105, and spring 106 allowing it to swing about its center 115. The secondary rolls are mounted in a like manner, Fig. XI showing a section through roll 72. Roll 72 is mounted in bracket 107 which is secured to backing plate 108 by screws 109. 70 The secondary roll swings about its center 110

and is held against arm 10 by stud 11, nuts 12 and 13 and spring 14.

This arrangement of holding the roll brackets to the frame of the machine permits swinging of said brackets under the action of the automatic mechanism for angular adjustment, without the necessity of loosening or tightening bolts. It also permits the removal of the roll brackets without disturbing the angling mechanism, since said mechanism is attached to the backing plates.

I have herein shown and described various forms embodying the fundamental features of my invention and although structural modifications, and various other modifications can be made by any skilled worker in the art of cross-roll straightening machines, it is to be assumed that my invention embraces such changes and other modifications as come within the claims appended hereto.

I claim as my invention:

1. In a cross-roll straightening machine comprising a frame and at least one three-roll pass assembly comprising a concave primary roll rotatably mounted in the said frame and angularly adjustable angularly to adjust the axis of its rotation, two roll-carrying arms pivotally mounted in said frame for swinging movement toward and away from each other, means for swinging said arms and two concave secondary rolls rotatably carried by said arms in opposition to each other and to the said primary roll to form with the said primary roll a cross-rolls pass of regulable diameter for the reception of round stock, said secondary rolls being angularly adjustable angularly to adjust the axes of their rotation; and automatic means for angularly adjusting the said secondary rolls of the pass comprising linkages connected with each of the said angularly adjustable rolls and arranged automatically to correlate the angular positioning of the said rolls to pass-diameter determining positioning of the rolls in swinging movement of the said roll-carrying arms.
2. In a cross-roll straightening machine comprising a frame and at least one three-roll pass assembly comprising a concave primary roll rotatably mounted in the said frame and angularly adjustable angularly to adjust the axis of its rotation, two roll-carrying arms pivotally mounted in said frame for swinging movement toward and away from each other, means for swinging said arms and two concave secondary rolls rotatably carried by said arms in opposition to each other and to the said primary roll to form with the said primary roll a cross-rolls pass of regulable diameter for the reception of round stock, said secondary rolls being angularly adjustable angularly to adjust the axes of their rotation; automatic means for angularly adjusting the said secondary rolls of the pass comprising linkages connected with each of the said angularly adjustable rolls and arranged automatically to correlate the angular positioning of the said rolls to pass-diameter determining positioning of the rolls in swinging movement of the said roll-carrying arms, and structure comprised in said means for angular adjustment of the said rolls regulable to control the correlation between the angular positioning of the rolls and the said pass-diameter positioning of the rolls.
3. In a cross-roll straightening machine comprising a frame and at least one three-roll pass assembly comprising a concave primary roll rotatably mounted in a roll-carrying bracket, said roll-carrying bracket being angularly adjustable

in the said frame angularly to adjust the axis of rotation of the said primary roll, two roll-carrying arms pivotally mounted in said frame for swinging movement toward and from each other, two concave secondary rolls, and roll-carrying brackets rotatably carrying said rolls and mounted each in one of said arms for angular adjustment angularly to adjust the axes of rotation of said rolls, the two said secondary rolls being adjustable by swinging movement of said arms with respect to the said primary roll to form with the said primary roll a cross-roll pass of regulable diameter for the reception of round stock; and automatic means for angularly adjusting all the said rolls of the pass comprising linkages connected with the angularly adjustable roll-carrying brackets of each of the said rolls and arranged automatically to correlate the angular positioning of the said rolls to pass-diameter determining positioning of the rolls in swinging movement of the said roll-carrying arms.

4. In a cross-roll straightening machine comprising a frame and at least one three-roll pass assembly comprising a concave primary roll rotatably mounted in a roll-carrying bracket, said roll-carrying bracket being angularly adjustable in the said frame angularly to adjust the axis of rotation of said primary roll, two roll-carrying arms pivotally mounted in said frame for swinging movement toward and from each other, two concave secondary rolls, and roll-carrying brackets rotatably carrying said rolls and mounted each in one of said arms for angular adjustment angularly to adjust the axes of rotation of said rolls, the two said secondary rolls being adjustable by swinging movement of said arms with respect to the said primary roll to form with the said primary roll a cross-roll pass of regulable diameter for the reception of round stock; automatic means for angularly adjusting all the said rolls of the pass comprising linkages interconnecting the angularly adjustable roll-carrying brackets of each of the said rolls and arranged automatically to correlate the angular positioning of the said rolls to pass-determining positioning of the rolls in swinging movement of the said roll-carrying arms, and structure comprised in said means for angular adjustment of the said rolls regulable to control the correlation between the angular positioning of the rolls and the said pass-diameter positioning of the rolls.

5. In a cross-roll straightening machine comprising a frame and at least one three-roll pass assembly comprising a primary roll rotatably mounted in the said frame and angularly adjustable angularly to adjust the axis of its rotation, two roll-carrying arms pivotally mounted in said frame for swinging movement toward and away from each other, means for swinging said arms and two secondary rolls rotatably carried by said arms in opposition to each other and to the said primary roll to form with the said primary roll a cross-roll pass of regulable diameter for the reception of round stock, said secondary rolls being angularly adjustable angularly to adjust the axes of their rotation; and automatic means for angularly adjusting the said secondary rolls of the pass comprising linkages interconnecting the said angularly adjustable secondary rolls each with fixed structure to correlate the angular positioning of the said rolls to pass-diameter determining positioning of the rolls in swinging movement of the said roll-carrying arms.

6. In a cross-roll straightening machine com-

prising a frame and at least one three-roll pass assembly comprising a primary roll rotatably mounted in the said frame and angularly adjustable angularly to adjust the axis of its rotation, two roll-carrying arms pivotally mounted in said frame for swinging movement toward and away from each other, means for swinging said arms and two secondary rolls rotatably carried by said arms in opposition to each other and to the said primary roll to form with the said primary roll a cross-roll pass of regulable diameter for the reception of round stock, said secondary rolls being angularly adjustable angularly to adjust the axes of their rotation; automatic means for angularly adjusting the said secondary rolls of the pass comprising linkages interconnecting the said angularly adjustable secondary rolls each with fixed structure to correlate the angular positioning of the said rolls to pass-diameter determining positioning of the rolls in swinging movement of the said roll-carrying arms, and structure comprised in said means for angular adjustment of the secondary rolls regulable to control the correlation between the angular positioning of the said rolls and the said pass-diameter determining positioning of the rolls.

7. In a cross-roll straightening machine comprising a frame and at least one three-roll pass assembly comprising a primary roll rotatably mounted in the said frame and angularly adjustable angularly to adjust the axis of its rotation, two roll-carrying arms pivotally mounted in said frame for swinging movement toward and away from each other, means for swinging said arms and two secondary rolls rotatably carried by said arms in opposition to each other and to the said primary roll to form with the said primary roll a cross-roll pass of regulable diameter for the reception of round stock, said secondary rolls being angularly adjustable angularly to adjust the axes of their rotation; automatic means for angularly adjusting the said secondary rolls of the pass comprising linkages interconnecting the said angularly adjustable secondary rolls each with fixed structure automatically to correlate the angular positioning of the said rolls to pass-diameter determining positioning of the rolls in swinging movement of the said roll-carrying arms, and linkage connecting the said primary roll with one of the said roll-carrying arms effective in swinging movement of the said arm automatically to adjust the angular positioning of the said primary roll in accordance with pass-diameter regulating movement of the said arm.

8. In a cross-roll straightening machine comprising a frame and at least one three-roll pass assembly comprising a primary roll rotatably mounted in the said frame and angularly adjustable angularly to adjust the axis of its rotation, two roll-carrying arms pivotally mounted in said frame for swinging movement toward and away from each other, means for swinging said arms and two secondary rolls rotatably carried by said arms in opposition to each other and to the said primary roll to form with the said primary roll a cross-roll pass of regulable diameter for the reception of round stock, said secondary rolls being angularly adjustable angularly to adjust the axes of their rotation; automatic means for angularly adjusting the said secondary rolls of the pass comprising linkages interconnecting the said angularly adjustable secondary rolls each with fixed structure to correlate the angular positioning of the said rolls to pass-diameter determining positioning of the rolls in swinging movement of

the said roll-carrying arms, structure comprised in said means for angular adjustment of the secondary rolls regulable to control the correlation between the angular positioning of the said rolls and the said pass-diameter determining positioning of the rolls, and linkage connecting the said primary roll with one of the said roll-carrying arms effective in swinging movement of the said arm automatically to adjust the angular positioning of the said primary roll in accordance with pass-diameter regulating movement of the said arm.

9. In a cross-roll straightening machine comprising a frame and at least one three-roll pass assembly comprising a primary roll rotatably mounted in the said frame and angularly adjustable angularly to adjust the axis of its rotation, two roll-carrying arms pivotally mounted in said frame for swinging movement toward and away from each other, means for swinging said arms and two secondary rolls rotatably carried by said arms in opposition to each other and to the said primary roll to form with the said primary roll a cross-roll pass of regulable diameter for the reception of round stock, said secondary rolls being angularly adjustable angularly to adjust the axes of their rotation; automatic means for angularly adjusting the said secondary rolls of the pass comprising linkages interconnecting the said angularly adjustable secondary rolls each with fixed structure to correlate the angular positioning of the said rolls to pass-diameter determining positioning of the rolls in swinging movement of the said roll-carrying arms, linkage connecting the said primary roll with one of the said roll-carrying arms effective in swinging movement of the said arm automatically to adjust the angular positioning of the said primary roll in accordance with pass-diameter regulating movement of the said arm, and structure comprised in said means for angular adjustment of the said primary roll regulable to control the correlation between the angular positioning of the said roll and the said pass-diameter determining positioning of all the said rolls.

10. In a cross-roll straightening machine comprising a frame and at least one three-roll pass assembly comprising a concave primary roll rotatably mounted in the said frame and angularly adjustable angularly to adjust the axis of its rotation, two roll-carrying arms pivotally mounted in said frame for swinging movement toward and away from each other, means for swinging said arms and two concave secondary rolls rotatably carried by said arms in opposition to each other and to the said primary roll to form with the said primary roll a cross-roll pass of regulable diameter for the reception of round stock, said secondary rolls being angularly adjustable angularly to adjust the axes of their rotation; automatic means for angularly adjusting the said secondary rolls of the pass comprising linkages interconnecting the said angularly adjustable secondary rolls each with fixed structure to correlate the angular positioning of the said rolls to pass-diameter determining positioning of the rolls in swinging movement of the said roll-carrying arms, linkage connecting the said primary roll with one of the said roll-carrying arms effective in swinging movement of the said arm automatically to adjust the angular positioning of the said primary roll in accordance with pass-diameter regulating movement of the said arm, and structure comprised in the adjusting linkage of each of said rolls regulable to control the correlation be-

11

tween the angular positioning of the roll and the
said pass-diameter determining positioning of
the roll.
